UNITED STATES PATENT OFFICE.

JOHN E. CLEMENT, OF PEABODY, MASSACHUSETTS.

CUTTER FOR LEATHER-WHITENING MACHINES.

SPECIFICATION forming part of Letters Patent No. 259,497, dated June 13, 1882.

Application filed February 27, 1882. (No model.)

To all whom it may concern:

Be it known that I, JOHN E. CLEMENT, of Peabody, Essex county, Massachusetts, have invented a new and Improved Cutter for 5 Leather-Whitening Machines, of which the following is a full, clear, and exact description.

The invention consists in the combination, with a cylinder of a length slightly more than 10 its diameter and provided with V-shaped grooves, of V-shaped cutters provided with spiral wings and secured in the grooves of the cylinder by strips of soft metal, as hereinafter fully described.

15 Reference is to be had to the accompanying drawings, forming part of this specification, in which similar letters of reference indicate corresponding parts in all the figures.

Figure 1 is a transverse section of a cutter- 20 head provided with the improved knives. Fig. 2 is an edge view, and Fig. 3 a side view, of one knife or cutter; and Fig. 4 is a plan view, showing the relative position and arrangement of the cutters on the head.

25 A is the cutter-head, which is a cylinder of a length slightly more than its diameter, and B are the cutters, set in grooves formed in the head, and held securely by strips of soft metal (shown at a) calked or forced into the grooves 30 after the cutters are inserted.

The cutters B are thin blades of metal bent in V form, and with each wing b formed as a spiral on a pitch equal, or nearly so, to the

length of the cylinder. The points or angles of the double cutters are at the mid-length of 35 the head A, and the wings are of a length to extend to the ends of the head at each side.

The cutters, formed and arranged as described, act on the leather with a shearing cut from the center line outward in both directions, 40 the fiber being thereby cut in two directions, and the operation is similar to slicker-whitening as done by hand. The strain or draft on the leather is in both directions, the wings at one side acting against those at the other side. 45 There is no movement of the leather to either side, and it is retained on the bed-plate. Further, the cutters will not crease or plait the leather, and the liability of holes being cut is thus avoided. 50

The cutters, constructed as described, are self-bracing and not liable to bend or to break.

Having thus described my invention, I claim as new and desire to secure by Letters Patent—

The combination, with the cylinder A, of a 55 length slightly more than its diameter and provided with V-shaped grooves, of the V-shaped cutters B, provided with spiral wings b, and secured in the grooves of the cylinder by the strips of soft metal a, substantially as herein 60 shown and described, and for the purpose set forth.

JOHN EDWARD CLEMENT.
